(57) CLAIM

The ornamental design for a work table, as shown and described.

DESCRIPTION

FIG. 1 is an isometric view of the top of the work table of the present invention as a whole.

FIG. 2 is a top view of the top of the work table of the present invention in plan.

FIG. 3 is a side view of the work table of the present invention; and,

FIG. 4 is a side view of the right edge of the work table of the present invention.

The oval-shaped work table has an oval cut-out, and a continuous curved and profiled edge on the outside perimeter of the work table.
